US00D704691S

(12) **United States Design Patent**
Kim et al.

(10) **Patent No.:** US D704,691 S
(45) **Date of Patent:** ** May 13, 2014

(54) **CASE FOR ELECTRONIC DEVICE**

(71) Applicant: **Samsung Electronics Co., Ltd.**,
Suwon-si (KR)

(72) Inventors: **Yoon-Young Kim**, Seongnam-Si (KR);
Won-Kyu Sung, Seongnam-Si (KR)

(73) Assignee: **Samsung Electronics Co., Ltd.**,
Suwon-si (KR)

(**) Term: **14 Years**

(21) Appl. No.: **29/448,603**

(22) Filed: **Mar. 13, 2013**

(51) LOC (10) Cl. **14-03**

(52) U.S. Cl.

USPC **D14/250**

(57) **CLAIM**

The ornamental design for a case for electronic device, as shown and described.

DESCRIPTION

FIG. 1 is a front perspective view of a case for electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top plan view thereof;
FIG. 7 is a bottom plan view thereof;

FIG. 8 is a perspective view of the case for an electronic device in an open state showing the exterior thereof; and,
FIG. 9 is a perspective view of the case for an electronic device in an open state showing the interior thereof.
The dash-dot broken lines represent the bounds of the claimed design while all other broken lines depict unclaimed environment; the broken lines form no part of the claimed design.

1 Claim, 7 Drawing Sheets
